(57) CLAIM

The ornamental design for an article of clothing with attached scarf, as shown and described.

DESCRIPTION

FIG. 1 is a perspective view of an article of clothing with attached scarf, showing my new design; and,

FIG. 2 is a perspective view thereof, showing the scarf portion of the invention used as a head covering.

The broken line showing of the human figure in FIG. 2 illustrates environment only that forms no part of the claim.

1 Claim, 2 Drawing Sheets
